UNITED STATES PATENT OFFICE.

CLARA FRESH, OF NEW BEDFORD, MASSACHUSETTS.

KNIFE-REST.

1,264,914.

Specification of Letters Patent.

Patented May 7, 1918.

Application filed June 9, 1917. Serial No. 173,684.

To all whom it may concern:

Be it known that I, CLARA FRESH, a subject of the Emperor of Austria, resident of New Bedford, county of Bristol, and State 5 of Massachusetts, have invented certain new and useful Improvements in Knife-Rests, of which the following is a specification.

This invention relates to improvements in rests or supports and particularly to types 10 adapted to be used upon tables from which food is served.

The principal object of the invention is to provide a rest upon which the blades of knives, forks and spoons and the like, may 15 be supported after having once been used so as to prevent soiling the linen on the table, the rest supporting the implement in such way that the same may be readily grasped when it is desired to make use of it.

20 A further object is to provide such devices in forms which may be cheaply manufactured, and which present an attractive appearance in harmony with the silver ware used.

25 These and other like objects are attained by the novel construction and combination of parts hereafter described and shown in the accompanying drawing, forming a material part of this disclosure, and in which:—

30 Figure 1 is a perspective view showing a support or rest made in accordance with the invention.

Fig. 2 is an enlarged fragmentary vertical sectional view, and

35 Fig. 3 is a further enlarged perspective view showing one end of the support rail.

The invention consists of a pair of oppositely disposed, substantially H shaped ornamental supports having curved legs 10, terminating in spherical feet 11, adapted to rest upon any level surface, as the linen table cover, without in any way injuring the same, the legs being connected by an integral center or hub 12, containing a rectangular 40 opening 14, suited to receive a correspondingly shaped tenon 16, formed at the ends of the support bar 17, the shoulders 18 of which are adapted to be drawn tightly against one side of the hub 12 by means of 45 screw-threaded knobs 20, arranged on the

opposite side and engaging with screws 21, having enlarged heads 22, the heads being secured in recesses 24, formed in the rectangular extensions 16, open at one side and through which is an open slot 25 receptive of 55 the screw-threaded shank portions of the screws 21.

Thus the main elements of the article are rigidly held together in such manner as to afford a convenient support for implements 60 as before mentioned.

It will be observable that the height of the rod 17, relative to the surface upon which the device stands, may be changed by turning the article upon its side, and it will be 65 understood that the device may be furnished in a highly ornamental manner and made of such material as may be desired.

Having thus described my invention, what I claim as new, and desire to secure by Letters Patent, is:—

1. In a device of the class described, the combination with a pair of substantially H shaped support elements, said elements having spherical extremities, of a rod extending 75 between said support elements, said rod having squared extensions at each end thereof and suited to enter corresponding openings formed in said support elements, screws removably engaged in said extensions, and 80 means for securing said support elements rigidly with said screws upon the opposite side of the supports from which said rod extends.

2. In a device of the class described, the 85 combination with a pair of substantially H shaped support elements having spherical terminals and containing rectangular openings, of a rod extending between said elements, rectangular extensions at the ends of 90 said rods adapted to be received within the openings within said supports, means for engaging screws in said extensions, and threaded knobs engageable with said screws adapted to be applied upon the outer side of 95 said supports.

In testimony whereof I have affixed my signature.

CLARA FRESH.

Copies of this patent may be obtained for five cents each, by addressing the "Commissioner of Patents, Washington, D. C."
